ATTORNEY.

INVENTOR.

UNITED STATES PATENT OFFICE.

JAMES F. McCLEARY, OF SAN FRANCISCO, CALIFORNIA.

CURLING-IRON HEATER.

SPECIFICATION forming part of Letters Patent No. 769,560, dated September 6, 1904.

Application filed March 29, 1904. Serial No. 200,544. (No model.)

To all whom it may concern:

Be it known that I, JAMES F. McCLEARY, a citizen of the United States, residing at San Francisco, in the county of San Francisco and 5 State of California, have invented certain new and useful Improvements in Curling-Iron Heaters, of which the following is a specification.

My invention relates to improvements in 10 curling-iron heaters, the object of my invention being to provide a device of this character which shall be cheap and simple in construction and which when not in use can be packed in a small compass for the purpose of 15 shipment or storage.

My invention therefore resides in the novel construction, combination, and arrangement 20 of parts for the above ends, hereinafter fully specified, and particularly pointed out in the 25 claim.

In the accompanying drawings, Figure 1 is a side elevation of the device in use. Fig. 2 is a side view of the device closed for shipment or storage. Fig. 3 is a perspective 25 view of an end of one of the clamping-arms.

Referring to the drawings, 1 represents a short tube which is adapted to be fitted over an ordinary gas-burner. From the lower end of this tube extend arms 2, which are bent 30 outward and then upwardly. Said tube and arms are made in a single piece of sheet metal which is sufficiently resilient to allow the arms to be brought close together, as shown in Fig. 2. The end of each arm is 35 formed with one upper claw 3 and two lower claws 4, which are adapted to engage the end of a tube 5, in which the curling-iron (shown

at 6) is inserted when the device is in position over a gas-flame. The upper claw 3 passes over the edge of the tube into the interior, 40 while the two lower claws at the same end pass beneath the edge of the tube on the exterior. Said claws thus firmly hold the ends of the tube, and the resiliency of the spring-arms holds the claw against said ends. The 45 tube 5 is in like manner preferably made of sheet metal, although not necessarily so. When not in use, the two arms are brought close together and are passed up into the tube 7, so that the whole device is then in very 50 compact form and can be contained in a narrow box, occupying little room. This saves expense in transportation. It is also much more convenient for use. A further advantage is that the parts can be made of sheet 55 metal, and the whole device is therefore very light and cheap.

I claim—

The combination of a tube adapted to be fitted over a gas-burner, resilient arms formed 60 integral with said tube and provided with claws at their outer ends, and a curling-iron-supporting tube engaged at its ends and supported by said claws, said resilient arms being adapted to enter said curling-iron-supporting cylinder for packing purposes, substantially as described.

In witness whereof I have hereunto set my hand in the presence of two subscribing witnesses.

JAMES F. McCLEARY.
